CLAIM

The ornamental design for a toilet bowl and cover assembly, as shown and described.

DESCRIPTION

FIG. 1 is a perspective view of a toilet bowl and cover assembly showing my new design;

FIG. 2 is a front view thereof;

FIG. 3 is a left side view thereof;

FIG. 4 is a right side view thereof; and,

FIG. 5 is a top view thereof.

The broken lines depict portions of the toilet seat and toilet cover that form no part of the claimed design.
